UNITED STATES PATENT OFFICE.

WILLIAM McLAUGHLIN, OF LOS ANGELES, CALIFORNIA.

BEVERAGE COOLER AND DISPENSER.

Application filed January 19, 1926. Serial No. 82,215.

My invention is a beverage cooler and dispenser adapted to contain liquids which have a certain amount of sediment and in which it is desired to stir up the sediment in dispensing.

An object of my invention is to provide a beverage cooler and dispenser in attractive form, particularly for dispensing beverages containing a considerable portion of sediment such as orange and other fruit juices.

A further object of my invention is to provide cooling devices such as ice containers which may be turned in the dispenser and thus stir the sediment at the same time cooling the liquid.

I preferably form my beverage cooler and dispenser as an imitation of the typical soda water bottle having the bottle structure divided on a horizontal line below the neck, the bottom portion of the bottle forming a liquid receptacle, the upper portion of the bottle with a typical metal cap forming a top closure. A stem extends downwardly through the top closure or cap and is supported by the foot which rests on the bottom of the lower portion of the bottle.

A yoke is attached to the stem and has suspended therefrom a pair of ice containers preferably formed of glass. The stem is jointed having a bayonet type of joint so that the upper portion with the neck portion of the bottle may be disconnected and a renewed supply of the beverage or ice inserted in the bottle structure or the ice containers without removing the latter if unnecessary.

A handle on the upper end of the stem allows the stem and the ice containers to be rotated to stir the contents of the bottle.

My invention will be more readily understood from the following description and drawings in which—

Figure 1 is a side elevation of my cooler and dispenser.

Fig. 2 is a vertical section therethrough.

Fig. 3 is a horizontal section on the line 3—3 of Fig. 2.

Fig. 4 is two views of the bayonet joint for the stem.

My beverage cooler comprises a structure simulating a soda water bottle as indicated generally by the numeral 1 having a lower or bottle portion 2 for containing the beverage, a neck portion 3, these being

fitted together by a tongue joint 4. A cap 5 which simulates the ordinary metal cap of a soda water bottle is secured to the top of the neck and has an aperture 6 therethrough.

A stand designated generally by the numeral 7, for insertion in the bottle, having a foot 8 forms the base. A supporting stem 9 extends upwardly from the base and has a bayonet joint 10 connecting it with the operating stem 11, the latter having transverse pins 12 to engage the bayonet joint. A handle 13 is secured to the upper end of the operating stem and may be used for raising and lowering same or for rotating it. A yoke 14 is secured to the stem 9 preferably above the joint 4 and has a plurality of openings 15 in which are suspended the ice containers 16; these latter having a rim 17 to allow their support from the yoke. A spigot or the like 18 forms the means for dispensing the liquid.

The manner of use of my beverage cooler and dispenser is substantially as follows:

By means of the bayonet connection of the operating stem 11 and the supporting stem 9 the bottle neck may be removed lifting the ice containers therewith if desired or the operating stem can be detached from the supporting stem allowing free removal of the bottle neck and the handle; the ice containers being removable than by the upper end of the supporting stem. This allows thorough cleansing of the lower or bottle portion of the dispenser. The ice may be filled in the ice containers either while there is beverage in the bottle or before the insertion of the ice containers in position.

The ice containers are supported on the supporting stand on the bottom of the bottle where there is substantially no weight from the containers on the bottle neck or the joint, when it is desired to stir the liquid the handle is rotated, thus rotating the ice containers, the supporting stem and the foot. This thoroughly agitates the sediment and brings the cooling ice containers into intimate contact with the liquid to be dispensed, thereby thoroughly cooling same.

It is preferable to make the dispensing bottle of glass and the ice containers also of glass as these are more attractive to the public and cause more ready sales than the enclosed containers in which the contents or the ice are invisible. However, it has

been found that glass ice containers frequently break and a dispensing station has no means of cooling the beverage, thereby, by mounting a plurality of ice containers in the bottle, even if one is broken the others may be utilized for cooling purposes. In the structure shown I illustrate only two ice containers, but it is to be understood that more may be utilized if desired.

10 Although my invention is of simple character, nevertheless it will be apparent that it may be changed in general construction or specific details to suit particular types of liquid dispensers, such changes being within 15 the scope of my invention as set forth in the description, drawings and claims.

It will be noted that the neck portion 3 has considerable outward bulge above the joint 4 to allow for stirring the beverage 20 by reciprocating the stand with the ice containers up and down. When agitated in this manner the foot 8 thoroughly stirs the contents of the dispenser.

Having described my invention, what I 25 claim is:

1. A beverage cooler comprising in combination a liquid receptacle, a stand supported in said receptacle and a plurality of ice containers insertable through the top 30 of the receptacle and movable therein to agitate the beverage.

2. A beverage cooler as claimed in claim 1, in which the stand is supported on the base of the receptacle and is provided with an upward extension to allow rotation of the 35 stand and the containers.

3. A beverage cooler and dispenser comprising in combination a structure simulating a bottle having a lower portion forming a liquid receptacle and an upper portion forming a neck separable one from the other, a stand in the receptacle portion having a plurality of ice containers supported thereby and means extending through the neck to 40 rotate the ice containers.

4. A beverage cooler comprising in combination a structure simulating a bottle having a lower portion forming a beverage receptacle, an upper portion forming a bottle neck, the lower and upper portions being separable, a cap on the neck portion, a stand supported in the lower portion having a yoke and a plurality of ice containers depending from the yoke.

5. A beverage cooler as claimed in claim 4, having in addition an operating stem extending downwardly through the cap detachably connected to the stand, said operat-

ing stem being adapted to rotate the ice containers.

6. A liquid beverage cooler and dispenser comprising in combination a bottle-like structure having a lower portion forming a beverage receptacle, an upper portion forming a neck, a cap on top of the neck, the neck being separable from the lower portion, a stand having a foot mounted in the beverage receptacle, the foot resting on the base of said receptacle, a supporting stem extending upwardly from the base, a yoke mounted on the stem, a plurality of ice containers depending from the yoke, an operating stem detachably connected to the supporting stem, and extending upwardly through the cap and means on the upper end of the operating stem to rotate the stand and ice containers.

7. In a beverage cooler and dispenser, a liquid receptacle, a stand having a foot resting on the base of the receptacle and a supporting stand extending upwardly from the base, a yoke attached to the supporting stand and extending horizontally therefrom, a plurality of tubular ice containers depending from the yoke into the liquid receptacle and means to rotate the supporting stand.

8. In a beverage cooler and dispenser as claimed in claim 7, having in addition a closure element resting on the top of the beverage receptacle having an opening through the top and an operating stem extending downwardly through said opening and detachably connected to the supporting stem forming the means for rotating the supporting stem and stand.

9. In a beverage cooler and dispenser, a support for ice containers comprising a central supporting stand, a foot forming a base therefor, said foot being adapted to stand on the base of the liquid receptacle, a yoke attached to the upper portion of the supporting stand having a plurality of openings and ice containers inserted through said openings and depending from the yoke.

10. In a beverage cooler and dispenser as claimed in claim 9, having in addition an operating stem detachably connected to the supporting stand, said operating stem being adapted to extend upwardly through a cover for a liquid receptacle and forming means exterior to the cover for rotating the ice containers.

In testimony whereof I have signed my name to this specification.

WM. McLAUGHLIN,
